UNITED STATES PATENT OFFICE.

EMIL MAX SCHNEIDENBACH, OF FRIEDRICHSHAGEN, NEAR BERLIN, GERMANY.

DRIVING MECHANISM FOR WATER CRAFT.

1,420,579.

Specification of Letters Patent. Patented June 20, 1922.

Application filed March 29, 1922. Serial No. 547,804.

To all whom it may concern:

Be it known that I, EMIL MAX SCHNEIDENBACH, a citizen of Germany, residing at Friedrichshagen, near Berlin, Germany, have invented certain new and useful Improvements in or Relating to Driving Mechanism for Water Craft; and I do hereby declare the following to be a full, clear, and exact description of the invention, such as will enable others skilled in the art to which it appertains to make and use the same.

A desire has long existed among amateurs of aquatics to be able to propel boats, especially those employed for sport, by means operated by the occupant. For example, manually operated screw propeller gearing, the train of gears being enclosed in a casing, has been tried without any considerable success. Pedal driven gear has been more favoured. The main advantages of such a form of drive are (1) the power of the leg muscles is considerably greater and far less quickly exhausted than that of the muscles of the arms, (2) the passenger can keep his eyes in the direction in which he is travelling and has his hands free for steering, (3) oars, with their wide reach, are dispensed with and therefore narrower waterways can be more readily traversed, (4) the position of the passenger in the boat is the same as in ordinary rowing boats and his legs are able to work in a similar position as when cycling, (5) the pedal gear consisting of enclosed standard units may be easily mounted in and detached from the boat, and in boats with a plurality of seats the arrangement of other pedal gears to the other seats and acting on a common shaft increases the utility of the boat without interfering with the water-line of the boat.

Attempts have been made to solve this problem for a considerable time and in a great variety of ways, but, for the most part, without success, since nearly all inventions relating to this matter consist of cumbrous devices for transmitting motion for which in most of the cases it was necessary to provide a suitable form of boat or to alter the arrangement of the seats or thwarts, whereas the requirements are just the opposite. Furthermore, these previous attempts relate nearly always to fixtures, not easily to be applied by anyone but an experienced boatbuilder, and being of considerable size and weight and mostly ar-

ranged on the stern of the boat, the water-line of the craft is disadvantageously influenced by the displacement of load, thus impairing the running efficiency of the boat.

Moreover, in various known constructions of this kind, the balance of the boat would be upset by raising the centre of gravity such as the operator standing in the boat or riding on a saddle, or seat arranged higher than usual. Pedal driving gears capable of being easily fitted to existing boats wherein the passengers or operators are placed in the usual seating position are in great demand.

The present invention is intended to approximate more closely to a practical solution of the above problems, inasmuch as all the requisite preliminary conditions have been carefully taken into consideration.

The advantage of the invention consists in the fact that the dimensions and weight of the device have been reduced to a minimum, so that whilst it does not in any way spoil the appearance of light boats used in aquatic sports, it nevertheless meets all the practical requirements hereinbefore enumerated.

In the drawing:

Fig. 1 is a side elevation, partly in section, showing the power transmitting mechanism.

Fig. 2 is a fragmentary sectional view of a boat, showing more particularly the installation of several sets of the apparatus arranged in tandem.

Fig. 3 illustrates a sailing boat, with parts broken away to show the installation of the apparatus.

The pedal driving gear comprises two pillars secured to a base plate that can be readily fixed in and detached from the boat, for supporting the pedal crank and several countershafts carrying interchangeable transmission gear or chain wheels, to which the driving force may be transmitted from the said crank by means of bevel gears directly to a main propeller shaft at a suitable ratio, the whole gear constructed as a standard unit being enclosed in a thin metal casing.

The device for transmitting foot power to the propeller is illustrated in Fig. 1, and its mode of action will be readily apparent. The motion of the pedals *a* is transmitted from the crank shaft *b* by the bevel pinions

c and *d* and through the pinions *e*, *f*, *g*, *h*, *i* to the shaft *k*. This shaft, which, when several sets of the apparatus are regularly or irregularly placed in the one boat, is connected by means of ball joints, acts on the propeller.

The pinions *e* and *f*, are mounted respectively upon the stub shafts *e'* and *f'*, while the pinions *g* and *h* are both mounted upon 10 a stub shaft *g'*, and the pinion *i* is rigid with the shaft *k*. All of the said shafts, as well as the crank shaft *b*, are journaled in the upright standards or pillars *p* and *p'*, which are rigidly secured to the base plate *o*, which 15 also carries the sheet metal casing or housing *o'*, having a cap or cover *o''* serving to enclose the various elements, all as will be clear from Fig. 2.

In the case of light rowing boats, a speed 20 of about 50 revolutions of the pedals per minute, is translated into about 750 revolutions of the screw. In order to avoid having the crank shaft, and consequently the whole machine, wider than in a bicycle and spreading 25 the legs too far apart, and also to avoid having to mount the pedal shaft any higher above the bottom of the boat than is necessary to clear the pedals in rotating, so that there may be no unfavourable alterations in 30 the point of application of the force and centre of gravity, which would cause instability and also to enable the propeller shaft to be mounted as close as possible to the bottom of the boat, the transmission is distributed 35 among several small pinions and shafts, the number of which is selected, in each case, in accordance with the desired ratio of transmission. The transmission of speed and power from one shaft to another may also, 40 in certain cases, be effected by means of chain wheels.

Fig. 2 represents a light sporting boat in which the power from several sets of the apparatus, arranged in tandem, is transmitted 45 to the common main shaft. This figure also

illustrates a form of seat which enables the user to assume such a convenient position as to ensure the fullest development of the power of the feet on the pedal gear. Each seat is mounted, by means of pivots *l* or by 50 bars *m* on lateral racks or perforated bars *n*, and is so adapted to be adjusted in relation to the pedal apparatus in accordance with the bodily dimensions of the user.

Figure 3 represents a sailing boat provided with a center board *r* operated in the well known manner by the rope or cable *r'*. The boat is further equipped with a pedal drive, as an auxiliary motor for use in calms, which can be easily set up when wanted, and 60 detachably secured in a very simple manner by known means. It is connected to the screws by means of a flexible shaft *s*, and a readily detachable coupling member *s'*, whereby it may be dismounted when not required, for storage, in any convenient place.

Having now particularly described and ascertained the nature of my said invention and in what manner the same is to be performed, I declare what I claim is:

A boat propelling mechanism comprising a base plate; a plurality of upright pillars rigidly secured to said base plate; a plurality of shafts journaled in said pillars; power transmitting connections between said 75 shafts; a casing carried by said base plate enclosing said pillars, shafts, and connections; a detachable flexible connection between one of said shafts and the propeller of said boat; a shaft journaled in one of said pillars substantially at right angles to said other shafts and extending through said casing; power transmitting connections within said casing between said last mentioned shaft and one of said other shafts; and foot 80 operated crank members carried by said last mentioned shaft, whereby power may be supplied to the mechanism.

In testimony whereof I affix my signature.
EMIL MAX SCHNEIDENBACH.
